(57) **ABSTRACT**

An antenna includes a dielectric layer, a conductive ground layer formed on a first main surface of the dielectric layer, and radiation elements formed on a second main surface of the dielectric layer and are conductive. The first radiation element includes a first non-uniform width part that has a width in a direction parallel to a first side in a linear shape opposed to a first vertex, and the width of the first non-uniform width part gradually decreases in a direction from the first side to the first vertex. The second radiation element includes a second non-uniform width part that has a width in a direction parallel to a second side in a linear shape opposed to a second vertex, and the width of the second non-uniform width part gradually decreases in a direction from the second side to the second vertex.

ANTENNA WITH RADIATION ELEMENT HAVING NON-UNIFORM WIDTH PART

TECHNICAL FIELD

The present disclosure relates to an antenna.

BACKGROUND ART

Patent Literature 1 discloses an array antenna of a direct feeding system and a coplanar feeding system. The direct feeding system refers to a feeding system in which a feed line is directly connected to an antenna element. The coplanar feeding system refers to a feeding system in which a feed line and an antenna element are formed on a common plane.

As described in Patent Literature 1, a conductive ground layer is formed on one of surfaces of a dielectric substrate, and a plurality of antenna elements and a plurality of feed lines are formed on the other surface of the dielectric substrate. The plurality of antenna elements are linearly aligned, and a feed line extends from each of the antenna elements. Terminals of the feed lines extending from end antenna elements located at both ends of a row of the antenna elements are open, and the end antenna elements are parasitic elements. Terminals of the feed lines extending from middle antenna elements other than the end antenna elements are connected to a transmission and reception circuit, and the middle antenna elements are driven elements. The parasitic elements at the both ends are provided for reducing a difference in directivity of the driven elements.

CITATION LIST

Patent Literature

Patent Literature 1: JP 2017-046107A

SUMMARY OF INVENTION

Technical Problem

Even for a directional antenna that strongly transmits and receives a radio wave in a specific direction, a wide range of a radiation direction in which a radio wave is strongly transmitted and received is preferable.

Thus, the present disclosure has been made in view of the circumstances described above, and an objective thereof is to provide an antenna having a wide range of a radiation direction in which a radio wave can be strongly transmitted and received.

Solution to Problem

A main aspect of the disclosure to achieve the above objective is an antenna comprising: a dielectric layer including a first main surface and a second main surface opposite to the first main surface;

a conductive ground layer formed on the first main surface;

a first radiation element that is formed on the second main surface and is conductive; and

a second radiation element that is formed side by side with the first radiation element on the second main surface and is conductive, wherein

the first radiation element includes a first non-uniform width part having a width in a direction parallel to a

2

first side in a linear shape opposed to a first vertex part, the width of the first non-uniform width part gradually decreasing in a direction from the first side to the first vertex part, and

the second radiation element includes a second non-uniform width part having a width in a direction parallel to a second side in a linear shape opposed to a second vertex part, the width of the second non-uniform width part gradually decreasing in a direction from the second side to the second vertex part.

Other features of the present disclosure are made clear by the following description and the drawings.

Advantageous Effects of Invention

With the present disclosure, a range of a radiation direction in which an antenna can strongly transmit and receive a radio wave is wide.

BRIEF DESCRIPTION OF DRAWINGS

FIG. 1 is a perspective view of an antenna according to a first embodiment.

FIG. 2 is a plan view of a conductive pattern layer of the antenna according to the first embodiment.

FIG. 3 is a plan view of a conductive pattern layer of an antenna according to a modified example of the first embodiment.

FIG. 4 is a plan view of a conductive pattern layer of an antenna according to a second embodiment.

FIG. 5 is a plan view of a conductive pattern layer of an antenna according to a third embodiment.

FIG. 6 is a plan view of a conductive pattern layer of an antenna according to a fourth embodiment.

FIG. 7 is a graph illustrating a relationship between a reflection coefficient and a frequency of the antenna according to the modified example of the first embodiment.

FIG. 8 is a graph illustrating a relationship between a gain and a radiation direction of the antenna according to the modified example of the first embodiment.

FIG. 9 is a graph illustrating a relationship between a reflection coefficient and a frequency of the antenna according to the second embodiment.

FIG. 10 is a graph illustrating a relationship between a gain and a radiation direction of the antenna according to the second embodiment.

FIG. 11 is a graph illustrating a relationship between a reflection coefficient and a frequency of the antenna according to the third embodiment.

FIG. 12 is a graph illustrating a relationship between a gain and a radiation direction of the antenna according to the third embodiment.

FIG. 13 is a graph illustrating a relationship between a reflection coefficient and a frequency of an antenna according to a comparative example.

FIG. 14 is a graph illustrating a relationship between a gain and a radiation direction of the antenna according to the fourth embodiment.

DESCRIPTION OF EMBODIMENTS

At least the following matters are made clear from the following description and the drawings.

Disclosed is an antenna including: a dielectric layer including a first main surface and a second main surface opposite to the first main surface; a conductive ground layer formed on the first main surface; a first radiation element

that is formed on the second main surface and is conductive; and a second radiation element that is formed side by side with the first radiation element on the second main surface and is conductive, wherein the first radiation element includes a first non-uniform width part having a width in a direction parallel to a first side in a linear shape opposed to a first vertex part, the width of the first non-uniform width part gradually decreasing in a direction from the first side to the first vertex part, and the second radiation element includes a second non-uniform width part having a width in a direction parallel to a second side in a linear shape opposed to a second vertex part, the width of the second non-uniform width part gradually decreasing in a direction from the second side to the second vertex part.

In this way, since the first radiation element including the first non-uniform width part and the second radiation element including the second non-uniform width part are arranged side by side, it is possible to widen a range of a radiation direction in which the antenna can strongly transmit and receive a radio wave.

The first non-uniform width part includes the first vertex part, the first radiation element includes a first uniform width part continuous from the first non-uniform width part toward the first side, the first uniform width part includes the first side, and a width of the first uniform width part is uniform in the direction parallel to the first side, the second non-uniform width part includes the second vertex part, the second radiation element includes a second uniform width part continuous from the second non-uniform width part toward the second side, and the second uniform width part includes the second side, and a width of the second uniform width part is uniform in the direction parallel to the second side.

With this configuration, since the first radiation element includes the first non-uniform width part and the first uniform width part, and the second radiation element next to the first radiation element includes the second non-uniform width part and the second uniform width part, it is possible to further widen a range of a radiation direction in which the antenna can strongly transmit and receive a radio wave.

A side of both side parts of the first non-uniform width part may be formed in a linear shape, and a side of both side parts of the second non-uniform width part may be formed in a linear shape.

Sides of the first non-uniform width part in both side parts may be formed in a curved shape, and sides of the second non-uniform width part in both side parts may be formed in a curved shape.

The first radiation element may have a shape that is line symmetric with respect to a perpendicular line from the first vertex part to the first side, and the second radiation element may have a shape that is line symmetric with respect to a perpendicular line from the second vertex part to the second side.

The second side and the first side may be arranged on a straight line.

The first radiation element and the second radiation element may be symmetrical with respect to a symmetry line located between the first radiation element and the second radiation element and perpendicular to the first side.

The antenna may further include: a first feed line that is formed on the second main surface, extends from the first vertex part, and is conductive; a second feed line that is formed on the second main surface, extends from the second vertex part, is electrically connected to an end portion of the first feed line distal from the first radiation element, and is conductive; and a transmission line that extends from the

end portion of the first feed line distal from the first radiation element and an end portion of the second feed line distal from the second radiation element, and is conductive.

The transmission line may extend perpendicularly to the first side from the end portion of the first feed line distal from the first radiation element and the end portion of the second feed line distal from the second radiation element in a direction from the first side to the first vertex part, and the first radiation element and the second radiation element may be line symmetrical with respect to a center line of the transmission line, and the first feed line and the second feed line may be line symmetrical with respect to the center line of the transmission line.

15

EMBODIMENTS

Embodiments of the present disclosure are described below with reference to the drawings. Note that, although various limitations that are technically preferable for carrying out the present disclosure are imposed on the embodiments to be described below, the scope of the present disclosure is not to be limited to the embodiments and illustrated examples below.

25

First Embodiment

FIG. 1 is a perspective view of an antenna 1.

The antenna 1 is used for transmitting, receiving, or both transmitting and receiving a radio wave in a frequency band of a microwave or a millimeter wave.

The antenna 1 is a microstrip antenna. The antenna 1 includes a dielectric layer 10, a conductive pattern layer 20 formed on one of main surfaces of the dielectric layer 10, and a conductive ground layer 30 formed on the other main surface of the dielectric layer 10. Here, main surfaces of a layer refer to a surface on a front side of the layer and a surface on an opposite side to the front side. Note that a protective dielectric layer may be formed on one of the main surfaces of the dielectric layer 10 so as to cover the conductive pattern layer 20, and in addition to this or instead of this, a protective dielectric layer may cover the conductive ground layer 30.

The dielectric layer 10 is formed of a resin (e.g., a liquid crystal polymer or a polyimide), a fiber-reinforced resin (e.g., a glass fiber-reinforced epoxy resin, a glass-cloth base material epoxy resin, or a glass-cloth base material polyphenylene ether resin), a fluoropolymer, or a ceramic. The dielectric layer 10 may be a single layer body, or may be a layered body. The dielectric layer 10 may be flexible, or may be rigid.

The conductive pattern layer 20 and the conductive ground layer 30 are formed of a conductive metal material such as copper.

FIG. 2 is a plan view of the conductive pattern layer 20. FIG. 2 illustrates, as auxiliary lines or symbols representing directions, an X axis, a Y axis, and a Z axis orthogonal to each other. The Z axis is parallel to a thickness direction of the dielectric layer 10, and is perpendicular to a radiation surface (one of the main surfaces of the dielectric layer 10 on which the conductive pattern layer 20 is formed) of the antenna 1.

The conductive pattern layer 20 is shape-processed (patterned) by a subtractive method, an additive method, or the like, for example. In this way, a first feed line 22, a second feed line 23, a transmission line 24, a first radiation element 25, and a second radiation element 26 are formed in the conductive pattern layer 20.

The first radiation element 25 is formed in a pentagon symmetrical with respect to a symmetry line 25u parallel to the Y axis through a vertex 25j. The symmetry line 25u is also a perpendicular line from the vertex 25j to an opposite side 25a. Hereinafter, the vertex 25j is also referred to as a first vertex 25j, and the side 25a opposite to the first vertex 25j is also referred to as a first side 25a.

All of sides 25a, 25b, 25c, 25d, and 25e of the first radiation element 25 are straight lines. The first side 25a opposite to the first vertex 25j is parallel to the X axis, the sides 25b and 25c respectively extending from both ends of the first side 25a are parallel to the Y axis, and the sides 25b and 25c have lengths equal to each other. Since the sides 25b and 25c are parallel to each other, a width W1 in an X-axis direction of a region 25s of the first radiation element 25 sandwiched between the sides 25b and 25c is uniform from vertexes 25f and 25g to vertexes 25h and 25i. Hereinafter, the region 25s is referred to as a first uniform width part 25s.

An interior angle at the vertexes 25f and 25g at both ends of the first side 25a is a right angle. An interior angle at the vertex 25h opposite to the vertex 25f with respect to the side 25b is an obtuse angle, an interior angle at the vertex 25i opposite to the vertex 25g with respect to the side 25c is an obtuse angle, and the interior angle at the vertex 25h and the interior angle at the vertex 25i are equal to each other. A length of the side 25d extending from the vertex 25h to the first vertex 25j and a length of the side 25e extending from the vertex 25i to the first vertex 25j are equal to each other.

The sides 25d and 25e are inclined to the first side 25a so as to come closer to each other toward the first vertex 25j. Thus, a width W2 in the X-axis direction of a region 25t of the first radiation element 25 sandwiched between the sides 25d and 25e gradually decreases in a direction from the first side 25a to the first vertex 25j, and a maximum width in the region 25t is equal to the width W1 of the first uniform width part 25s. Hereinafter, the region 25t is referred to as a first non-uniform width part 25t.

An interior angle at the first vertex 25j is an acute angle. However, an interior angle at the first vertex 25j may be a right angle or an obtuse angle.

The first radiation element 25 and the second radiation element 26 are arranged in a row in the X-axis direction. Since a shape of the second radiation element 26 and a shape of the first radiation element 25 are symmetrical with respect to a symmetry line 27 that is parallel to the symmetry line 25u and is located between the first radiation element 25 and the second radiation element 26, the shape of the second radiation element 26 and the shape of the first radiation element 25 are congruent. Therefore, the second radiation element 26 is formed in a pentagon symmetrical with respect to a symmetry line 26u parallel to the Y axis through a vertex 26j. The symmetry line 26u is also a perpendicular line from the vertex 26j to a side 26a opposite to the vertex 26j. Hereinafter, the vertex 26j is also referred to as a second vertex 26j, and the side 26a opposite to the second vertex 26j is also referred to as a second side 26a.

The second side 26a is parallel to the X axis, and the second side 26a and the first side 25a are arranged on a straight line. Sides 26b and 26c respectively extending from both ends of the second side 26a are parallel to the Y axis, and the sides 26b and 26c have lengths equal to each other. Because the sides 26b and 26c are parallel to each other, a width W3 in the X-axis direction of a region 26s of the second radiation element 26 sandwiched between the sides 26b and 26c is uniform from vertexes 26f and 26g to vertexes 26h and 26i. Hereinafter, the region 26s is referred to as a second uniform width part 26s.

An interior angle at the vertexes 26f and 26g at both ends of the second side 26a is a right angle. An interior angle at the vertex 26h opposite to the vertex 26f with respect to the side 26b is an obtuse angle, an interior angle at the vertex 26i opposite to the vertex 26g with respect to the side 26c is an obtuse angle, and the interior angle at the vertex 26h and the interior angle at the vertex 26i are equal to each other. A length of a side 26d extending from the vertex 26h to the second vertex 26j and a length of a side 26e extending from the vertex 26i to the second vertex 26j are equal to each other.

The sides 26d and 26e are inclined with respect to the second side 26a so as to come closer to each other toward the second vertex 26j. Thus, a width W4 in the X-axis direction of a region 26t of the second radiation element 26 sandwiched between the sides 26d and 26e gradually decreases in a direction from the second side 26a to the second vertex 26j, and a maximum width in the region 26t is equal to the width W3 of the second uniform width part 26s. Hereinafter, the region 26t is referred to as a second non-uniform width part 26t.

An interior angle at the second vertex 26j is an acute angle. However, an interior angle at the second vertex 26j may be a right angle or an obtuse angle.

The side 25b of the first radiation element 25 and the side 26c of the second radiation element 26 adjacent to each other are parallel to each other, and an interval D1 between the sides 25b and 26c is uniform from the vertexes 25f and 26g to the vertexes 25h and 26i. Because the widths W2 and W4 of the non-uniform width parts 25t and 26t of the radiation elements 25 and 26 in the X-axis direction gradually decrease in the direction from the sides 25a and 26a to the vertexes 25j and 26j, an interval D2 between the side 25d of the first radiation element 25 and the side 26e of the second radiation element 26 adjacent to each other gradually increases in the direction from the first side 25a to the first vertex 25j.

A proximal end portion of the first feed line 22 having an L shape is electrically connected to the first vertex 25j of the first radiation element 25. The first feed line 22 linearly extends in a negative Y-axis direction from the first vertex 25j of the first radiation element 25, is then bent 90°, and linearly extends in a positive X-axis direction, and an end portion of the first feed line 22 distal from the first radiation element 25 is electrically connected to one end portion 24b of the transmission line 24. In other words, the first feed line 22 includes a first feed line part 22a linearly extending in the negative Y-axis direction from the first vertex 25j of the first radiation element 25, and a second feed line part 22b linearly extending in the positive X-axis direction from an end portion of the first feed line part 22a distal from the first radiation element 25 to one end portion 24b of the transmission line 24.

A proximal end portion of the second feed line 23 having an L shape is electrically connected to the second vertex 26j of the second radiation element 26. The second feed line 23 linearly extends in the negative Y-axis direction from the second vertex 26j of the second radiation element 26, is then bent 90°, and linearly extends in a negative X-axis direction, and an end portion of the second feed line 23 distal from the second radiation element 26 is electrically connected to one end portion 24b of the transmission line 24. In other words, the second feed line 23 includes a third feed line part 23a linearly extending in the negative Y-axis direction from the second vertex 26j of the second radiation element 26, and a fourth feed line part 23b linearly extending in the negative X-axis direction from an end portion of the third feed line

part **23a** distal from the second radiation element **26** to one end portion **24b** of the transmission line **24**.

A physical length of the first feed line **22** and a physical length of the second feed line **23** are equal to each other. A physical length of the first feed line part **22a** of the first feed line **22** and a physical length of the third feed line part **23a** of the second feed line **23** are equal to each other, and a physical length of the second feed line part **22b** of the first feed line **22** and a physical length of the fourth feed line part **23b** of the second feed line **23** are equal to each other.

A shape of the second feed line **23** and a shape of the first feed line **22** are symmetrical with respect to the symmetry line **27**.

The transmission line **24** linearly extends in the negative Y-axis direction from the end portions of the feed lines **22** and **23** distal from the radiation elements **25** and **26**. A center line of the transmission line **24** coincides with the symmetry line **27**. Another end portion **24a** of the transmission line **24** is a feed point. In other words, the end portion **24a** of the transmission line **24** is connected to a terminal of a radio frequency integrated circuit (RFIC), which is not illustrated. The RFIC is a transmitter, a receiver, or a transceiver. Note that the transmission line **24** may function as a transformer that achieves impedance matching for the terminal of the RFIC and the feed lines **22** and **23**.

The radiation elements **25** and **26** having the shapes as described above are arranged in a row, and thus a range of a radiation direction in which the antenna **1** can strongly transmit and receive a radio wave is wide.

Note that, as illustrated in FIG. 3, notches **25k** and **25k** made by being cut from the first vertex **25j** toward the inside of the first radiation element **25** in parallel with the first feed line part **22a** may be formed at the first vertex **25j** of the first radiation element **25** on both sides of the first feed line part **22a**. Thus, the first feed line part **22a** is extended from the first vertex **25j** of the first radiation element **25** to the inside of the first radiation element **25**, and is electrically connected to the first radiation element **25** via an extended part **22c**. Since such notches **25k** and **25k** are formed, impedance matching is achieved between the first feed line **22** and the first radiation element **25**. Similarly, notches **26k** and **26k** made by being cut from the second vertex **26j** toward the inside of the second radiation element **26** in parallel with the third feed line part **23a** may be formed at the second vertex **26j** of the second radiation element **26** on both sides of the third feed line part **23a**, and the third feed line part **23a** may be extended from the second vertex **26j** of the second radiation element **26** to the inside of the second radiation element **26**, and be electrically connected to the second radiation element **26** via an extended part **23c**. The extended parts **22c** and **23c** have lengths equal to each other.

Second Embodiment

FIG. 4 is a plan view of a conductive pattern layer **20** of an antenna according to a second embodiment. Hereinafter, a difference between the antenna according to the second embodiment and the antenna according to the modified example (refer to FIG. 3) of the first embodiment will be described. A corresponding portion between the antenna according to the second embodiment and the antenna according to the modified example of the first embodiment is provided with the same reference sign.

In the modified example of the first embodiment, all of the sides **25a**, **25b**, **25c**, **25d**, and **25e** of the first radiation element **25** are straight lines. In contrast, in the second embodiment, sides **25d** and **25e** being both side parts of a

first non-uniform width part **25t** of a first radiation element **25** are formed in a curved convex shape. Similarly, sides **26d** and **26e** being both side parts of a second non-uniform width part **26t** of a second radiation element **26** are formed in a curved convex shape. Even when the sides **25d** and **25e** have a curved shape, a width **W2** of the first non-uniform width part **25t** in the X-axis direction gradually decreases in a direction from a first side **25a** to a first vertex **25j**. Even when the sides **26d** and **26e** have a curved shape, a width **W4** of the second non-uniform width part **26t** in the X-axis direction gradually decreases in a direction from a second side **26a** to a second vertex **26j**. The corresponding portion between the antenna according to the second embodiment and the antenna **1** according to the modified example of the first embodiment is similarly provided except for the point described above.

The radiation elements **25** and **26** having the shapes as described above are arranged in a row, and thus a range of a radiation direction in which the antenna according to the second embodiment can strongly transmit and receive a radio wave is wide.

Third Embodiment

FIG. 5 is a plan view of a conductive pattern layer **20** of an antenna according to a third embodiment. Hereinafter, a difference between the antenna according to the third embodiment and the antenna according to the modified example (refer to FIG. 3) of the first embodiment will be described.

In the modified example of the first embodiment, the first radiation element **25** and the second radiation element **26** are formed in a pentagon. In contrast, in the third embodiment, a first radiation element **125** and a second radiation element **126** are formed in a semicircle, a semi-ellipse, or a shape close to the semicircle or the semi-ellipse. Hereinafter, shapes of the first radiation element **125** and the second radiation element **126** will be described in detail.

The first radiation element **125** includes a first vertex part **125j**, and a first side **125a** opposite to the first vertex part **125j**. A perpendicular line from the first vertex part **125j** to the first side **125a** is a symmetry line **125u**, and the first radiation element **125** is formed in a semicircle, a semi-ellipse, or a shape close to the semicircle or the semi-ellipse symmetrical with respect to the symmetry line **125u**. The first side **125a** is formed linearly in parallel to the X axis.

A side **125d** extends from one end **125f** of the first side **125a** to the first vertex part **125j** and is curved, and a side **125e** extends from another end **125g** of the side **125a** to the first vertex part **125j** and is curved. The sides **125d** and **125e** are formed in a curved convex shape. Thus, the first radiation element **125** is formed of only a first non-uniform width part **125t**, and a width **W2** of the first non-uniform width part **125t** in the X-axis direction gradually decreases in a direction from the first side **125a** to the first vertex part **125j**.

The first radiation element **125** and the second radiation element **126** are arranged in a row in the X-axis direction. Because a shape of the second radiation element **126** and a shape of the first radiation element **125** are symmetrical with respect to a symmetry line **127** that is parallel to the symmetry line **125u** and is located between the first radiation element **125** and the second radiation element **126**, the shape of the second radiation element **126** and the shape of the first radiation element **125** are congruent. Therefore, the second radiation element **126** has a shape symmetrical with respect to a symmetry line **126u** parallel to the Y axis and goes through a vertex part **126j**. The symmetry line **126u** is also

a perpendicular line from the second vertex part **126j** to a second side **126a** opposite to the second vertex part **126j**.

A side **126d** extending from one end **126f** of the second side **126a** to the second vertex part **126j** is formed in a curved convex shape. A side **126e** extending from another end **126g** of the second side **126a** to the second vertex part **126j** is formed in a curved convex shape. Thus, the second radiation element **126** is formed of only a second non-uniform width part **126t**, and a width **W4** of the second non-uniform width part **126t** in the X-axis direction gradually decreases in a direction from the second side **126a** to the second vertex part **126j**. An interval **D2** between the side **125d** of the first radiation element **125** and the side **126e** of the second radiation element **126** adjacent to each other gradually increases in the direction from the first side **125a** to the first vertex part **125j**.

A proximal end portion of a first feed line **22** having an L shape is electrically connected to the first vertex part **125j** of the first radiation element **125**, and a proximal end portion of a second feed line **23** having an L shape is electrically connected to the second vertex part **126j** of the second radiation element **126**. Because shapes of the first feed line **22**, the second feed line **23**, and a transmission line **24** are the same as those in the modified example of the first embodiment, detailed description thereof will be omitted.

Notches **125k** and **125k** made by being cut from the first vertex part **125j** toward the inside of the first radiation element in parallel with a first feed line part **22a** are formed at the first vertex part **125j** of the first radiation element **125** on both sides of the first feed line part **22a** of the first feed line **22**. Similarly, notches **126k** and **126k** made by being cut in parallel with a third feed line part **23a** are also formed on both sides of the third feed line part **23a** of the second feed line **23**.

The radiation elements **125** and **126** having the shapes as described above are arranged in a row, and thus a range of a radiation direction in which the antenna according to the third embodiment can strongly transmit and receive a radio wave is wide.

Comparative Example

FIG. 6 is a plan view of a conductive pattern layer **220** of an antenna according to a comparative example. As illustrated in FIG. 6, in the comparative example, a shape of radiation elements **225** and **226** arranged in a row in the X-axis direction is a rectangular shape. Sides **225a** and **225j** of the first radiation element **225** parallel to each other are parallel to the X axis, other sides **225b** and **225c** parallel to each other are parallel to the Y axis, and a width **W5** of the first radiation element **225** in the X-axis direction is uniform. Sides **226a** and **226j** of the second radiation element **226** parallel to each other are parallel to the X axis, other sides **226b** and **226c** parallel to each other are parallel to the Y axis, and a width **W6** of the second radiation element **226** in the X-axis direction is uniform. An interval **D5** between the first radiation element **225** and the second radiation element **226** is uniform.

A radiation range of the antenna according to the first to third embodiments is wider than that of the antenna in the comparative example. Hereinafter, a radiation range of the antenna according to the first to third embodiments being wider and a radiation range of the antenna according to the comparative example being narrower are verified by a simulation.

<Verification>

FIG. 7 is a graph illustrating a simulation result of a relationship between a reflection coefficient and a frequency of the antenna **1** according to the modified example of the first embodiment. As illustrated in FIG. 7, the antenna according to the modified example of the first embodiment has a frequency characteristic such that a reflection coefficient **S11** of an S parameter takes a minimum value at a frequency of 28 [GHz].

FIG. 8 is a graph illustrating a simulation result of directivity of a radio wave at 28 [GHz] radiated by the antenna according to the modified example of the first embodiment. A horizontal axis indicates an angle with reference to the Z axis on a YZ plane, and a vertical axis indicates a gain. As illustrated in FIG. 8, a radiation direction achieving a maximum gain of 7.14 [dBi] is -30 [degree], and a range of a radiation direction in which a gain is within -3.00 [dBi] from the maximum gain is from -49.15 to +71.54 [degree].

FIG. 9 is a graph illustrating a simulation result of a relationship between a reflection coefficient and a frequency of the antenna according to the second embodiment. As illustrated in FIG. 9, the antenna according to the second embodiment has a frequency characteristic such that a reflection coefficient **S11** of an S parameter takes a minimum value near a frequency of 28 [GHz].

FIG. 10 is a graph illustrating a simulation result of directivity of a radio wave at 28 [GHz] radiated by the antenna according to the second embodiment. A horizontal axis indicates an angle with reference to the Z axis on the YZ plane, and a vertical axis indicates a gain. As illustrated in FIG. 10, a radiation direction achieving a maximum gain of 6.92 [dBi] is 8 [degree], and a range of a radiation direction in which a gain is within -3.00 [dBi] from the maximum gain is from -45.12 to +68.47 [degree].

FIG. 11 is a graph illustrating a simulation result of a relationship between a reflection coefficient and a frequency of the antenna according to the third embodiment. As illustrated in FIG. 11, the antenna according to the third embodiment has a frequency characteristic such that a reflection coefficient **S11** of an S parameter takes a minimum value near a frequency of 28 [GHz].

FIG. 12 is a graph illustrating a simulation result of directivity of a radio wave at 28 [GHz] radiated by the antenna according to the third embodiment. A horizontal axis indicates an angle with reference to the Z axis on the YZ plane, and a vertical axis indicates a gain. As illustrated in FIG. 11, a radiation direction achieving a maximum gain of 7.55 [dBi] is 2 [degree], and a range of a radiation direction in which a gain is within -3.00 [dBi] from the maximum gain is from -45.38 to +65.45 [degree].

FIG. 13 is a graph illustrating a simulation result of a relationship between a reflection coefficient and a frequency of the antenna according to the comparative example.

As illustrated in FIG. 13, the antenna according to the comparative example has a frequency characteristic such that a reflection coefficient **S11** of an S parameter takes a minimum value near a frequency of 28 [GHz].

FIG. 14 is a graph illustrating a simulation result of directivity of a radio wave at 28 [GHz] radiated by the antenna according to the comparative example. A horizontal axis indicates an angle with reference to the Z axis on the YZ plane, and a vertical axis indicates a gain. As illustrated in FIG. 14, a radiation direction achieving a maximum gain of 8.34 [dBi] is 2 [degree], and a range of a radiation direction in which a gain is within -3.00 [dBi] from the maximum gain is from -43.22 to +53.66 [degree].

11

It is clear from the simulation result above that a range of the radiation direction of the antenna 1 according to the modified example of the first embodiment is the widest. It is clear that a range of the radiation direction of the antenna according to the second embodiment is the second widest. It is clear that a range of the radiation direction of the antenna according to the third embodiment is the third widest. It is clear that a range of the radiation direction of the antenna according to the comparative example is the narrowest.

- 126t: Second non-uniform width part.

The invention claimed is:

1. An antenna comprising:
a dielectric layer including a first main surface and a second main surface opposite to the first main surface;
a conductive ground layer formed on the first main surface;
a first radiation element that is formed on the second main surface and is conductive; and
a second radiation element that is formed side by side with the first radiation element on the second main surface and is conductive, wherein
the first radiation element includes a first non-uniform width part having a width in a direction parallel to a first side in a linear shape opposed to a first vertex part, the width of the first non-uniform width part gradually decreasing in a direction from the first side to the first vertex part, and
the second radiation element includes a second non-uniform width part having a width in a direction parallel to a second side in a linear shape opposed to a second vertex part, the width of the second non-uniform width part gradually decreasing in a direction from the second side to the second vertex part,
wherein
the first non-uniform width part includes the first vertex part,
the first radiation element includes a first uniform width part continuous from the first non-uniform width part toward the first side,

12

the first uniform width part includes the first side, and a width of the first uniform width part is uniform in the direction parallel to the first side,

the second non-uniform width part includes the second vertex part,

the second radiation element includes a second uniform width part continuous from the second non-uniform width part toward the second side, and

the second uniform width part includes the second side, and a width of the second uniform width part is uniform in the direction parallel to the second side.

2. The antenna according to claim 1, wherein
a side of both side parts of the first non-uniform width part is formed in a linear shape, and a side of both side parts of the second non-uniform width part is formed in a linear shape.

3. The antenna according to claim 1, wherein
sides of the first non-uniform width part in both side parts are formed in a curved shape, and sides of the second non-uniform width part in both side parts are formed in a curved shape.

4. The antenna according to claim 1, wherein
the first radiation element has a shape that is line symmetric with respect to a perpendicular line from the first vertex part to the first side, and
the second radiation element has a shape that is line symmetric with respect to a perpendicular line from the second vertex part to the second side.

5. The antenna according to claim 1, wherein
the second side and the first side are arranged on a straight line.

6. The antenna according to claim 5, wherein
the first radiation element and the second radiation element are symmetrical with respect to a symmetry line located between the first radiation element and the second radiation element and perpendicular to the first side.

7. The antenna according to claim 1, further comprising:
a first feed line that is formed on the second main surface, extends from the first vertex part, and is conductive;
a second feed line that is formed on the second main surface, extends from the second vertex part, is electrically connected to an end portion of the first feed line distal from the first radiation element, and is conductive; and
a transmission line that extends from the end portion of the first feed line distal from the first radiation element and an end portion of the second feed line distal from the second radiation element, and is conductive.

8. The antenna according to claim 7, wherein
the transmission line extends perpendicularly to the first side from the end portion of the first feed line distal from the first radiation element and the end portion of the second feed line distal from the second radiation element in a direction from the first side to the first vertex part, and
the first radiation element and the second radiation element are line symmetrical with respect to a center line of the transmission line, and the first feed line and the second feed line are line symmetrical with respect to the center line of the transmission line.

9. An antenna comprising:
a dielectric layer including a first main surface and a second main surface opposite to the first main surface;
a conductive ground layer formed on the first main surface;

13

a first radiation element that is formed on the second main surface and is conductive; and
 a second radiation element that is formed side by side with the first radiation element on the second main surface and is conductive, wherein
 the first radiation element includes a first non-uniform width part having a width in a direction parallel to a first side in a linear shape opposed to a first vertex part, the width of the first non-uniform width part gradually decreasing in a direction from the first side to the first vertex part, and
 the second radiation element includes a second non-uniform width part having a width in a direction parallel to a second side in a linear shape opposed to a second vertex part, the width of the second non-uniform width part gradually decreasing in a direction from the second side to the second vertex part,
 wherein
 sides of the first non-uniform width part in both side parts are formed in a curved shape, and sides of the second non-uniform width part in both side parts are formed in a curved shape.
10. An antenna comprising:
 a dielectric layer including a first main surface and a second main surface opposite to the first main surface;
 a conductive ground layer formed on the first main surface;

5
10

a first radiation element that is formed on the second main surface and is conductive; and
 a second radiation element that is formed side by side with the first radiation element on the second main surface and is conductive, wherein
 the first radiation element includes a first non-uniform width part having a width in a direction parallel to a first side in a linear shape opposed to a first vertex part, the width of the first non-uniform width part gradually decreasing in a direction from the first side to the first vertex part, and
 the second radiation element includes a second non-uniform width part having a width in a direction parallel to a second side in a linear shape opposed to a second vertex part, the width of the second non-uniform width part gradually decreasing in a direction from the second side to the second vertex part,
 wherein
 the first radiation element has a shape that is line symmetric with respect to a perpendicular line from the first vertex part to the first side, and
 the second radiation element has a shape that is line symmetric with respect to a perpendicular line from the second vertex part to the second side.
